ELECTRIC SNAP SWITCH

Application filed October 5, 1929. Serial No. 397,495.

This invention relates to improvements in electric snap switches.

An object of the invention is to improve and simplify the construction and assembly of the parts of switches of the aforementioned character.

Another object is to provide a novel construction and arrangement of parts whereby the life or durability of switches of the aforementioned character is greatly increased.

Another object is to provide a novel form of snap switch which is substantially noiseless in operation.

Another object is to provide a novel interlocking arrangement of the switch parts whereby the number of parts and the time required to assemble the same are reduced to a minimum.

Another object is to embody the aforementioned features in high grade flush switches of the enclosed type.

Various other improvements in the details of construction of the switch elements will be apparent or will be specifically pointed out in the course of the following description.

The accompanying drawings illustrate certain preferred embodiments of the invention, which will now be described, it being understood that the invention is susceptible of embodiment in other forms without departing from the scope of the appended claims.

In the drawings, Fig. 1 is a top plan view of a single pole toggle flush switch of the enclosed type embodying my invention, the insulating cover member and the supporting lugs or elements having been omitted for purposes of illustration.

Fig. 2 is an enlarged vertical sectional view on the line 2—2 of Fig. 1.

Fig. 3 is a similar view on the broken line 3—3 of Fig. 1.

Fig. 4 is a view similar to Fig. 1, but showing a switch of the double pole type.

Fig. 5 is a view of the switch shown in Fig. 4, with the insulating cover member and one of the supporting lugs in position.

Fig. 6 is a view partly in plan and partly in section showing a carrier for a single pole switch, and illustrating the manner of at-

taching and insulating the movable contact elements with respect thereto.

Fig. 7 is a plan view of the movable contact elements and certain of the associated parts prior to attachment thereof to the carrier. 55

Fig. 8 is a plan view of a carrier adapted for use in a double pole, three-way or four-way switch.

Fig. 9 is an enlarged top plan view of the insulating base of a single pole switch, with all of the switch parts omitted for purposes of illustration. 60

Fig. 10 is a bottom plan view of the insulating cover member which is complementary to the base shown in Figs. 1 and 9. 65

Fig. 11 is a top plan view similar to Fig. 1, but with the insulating cover member and one of the supporting lugs in position.

Fig. 12 is a detail perspective view of one of the combined stationary contact and terminal members of the switch. 70

Fig. 13 is a similar view of another of the combined stationary contact and terminal members of the switch. 75

Fig. 14 is a plan view of a stamped sheet metal blank which may be employed in formation of the switch frame.

Fig. 15 is a perspective view of the switch frame as developed from the blank shown in Fig. 14, and 80

Fig. 16 is a perspective view of one of the soft rubber blocks or cushions upon which the switch frame is adapted to rest.

Referring to the drawings, the numeral 20 designates a preferred form of the molded insulating base of a single pole snap switch embodying my invention, said base having a flat upper face 21 and a flat lower face 22, the end portions of the lower face being offset upwardly as indicated at 23, 24 (Fig. 2) as is customary in this type of switch. Base 20 is relatively deeply recessed from the upper face thereof, as best illustrated at 25 and 26 in Figs. 2 and 9,—the recess 25 with its arcuate depression 27 being adapted to accommodate the switch frame and actuating mechanism and the recess 26 being adapted to accommodate the oscillatable bridging contact of the switch. 85 90 95 100

Extending throughout the depth of recess 25 and at opposite ends thereof are aligned channels 28 and 29, and extending upwardly a short distance from the bottom wall of recess 25 are pairs of integral shoulders or 5 abutments 30 and 31, the opposed walls 32 and 33 of which are convergent to form a pair of dovetail recesses at opposite ends of the insulating base.

10 Adapted to seat rather snugly within said dovetail recesses are a pair of correspondingly shaped soft or live rubber cushions or blocks 34 and 35, said blocks being of identical shape and size and one of the same being 15 illustrated in detail in Fig. 16. Said blocks are preferably formed by cutting into sections of the desired thickness a strip or bar of extruded rubber of the required shape in cross section,—care being exercised in the cutting operation to insure substantial parallelism of the cut faces of the blocks. The opposed smaller faces of the rubber blocks are provided with arcuate cut away portions or 20 vertical channels 34^a, 35^a for a purpose to be 25 described.

The switch frame, which is preferably made from a stamped sheet metal blank of the form illustrated in Fig. 14, comprises a flat base portion 36 having spaced substantially rectangular perforations 37 and 38, and the ends of said base portion being of reduced width, as indicated at 39 and 40, to fit within the aforementioned vertical channels 28 and 29 in base 20. The blank illustrated 30 in Fig. 14 is bent along the dotted lines 41 and 42 to provide the frame arms 43 and 44 extending upwardly at right angles to the base 36.

As shown the frame arms are provided 40 with relatively large perforations 45 and 46 of substantially inverted triangle shape, whereas the frame blank is punched out as indicated at 47 (Fig. 14) to provide a relatively wide cut away portion extending entirely 45 across the frame base and upwardly along the frame arms, thus leaving relatively narrow angular portions 48 and 49 integral with the frame arms or sides.

The frame arms 43 and 44 are of reduced 50 width above the perforations 45, 46,—said reduced portions being provided with aligned circular openings 50 and 51 to receive the headed pivot pin 52 (Figs. 2 and 3). Above the openings 50 and 51 the frame arms are 55 still further reduced in width as shown at 53 and 54,—right angled shoulders 55 and 56 being preferably provided between said reduced portions 43, 53 and 44, 54.

Pivotaly supported by the pin 52 between 60 the arms of the switch frame is a flat stamped sheet metal toggle lever or rocker 57, said lever having an upwardly extending arm 58 which is notched or otherwise suitably formed as indicated at 59 to provide a proper interlocking connection between the same and the

insulating handle portion 60 which is molded thereabout. Said handle portion is of only slightly less width than the space between the frame arms, so that the lever is constrained to move in a constant plane, that is, without substantial lateral movement or wobbling. Lever 57 is provided with relatively widely divergent curved arms or extensions 61 and 62 the ends of which are adapted to move alternately through the perforations 37 and 38 in the frame base and into engagement with the upper surfaces of the rubber blocks 34 and 35, respectively, whereby oscillatory movement of lever 57 in each direction is yieldably limited.

Also projecting from lever 57 at a point intermediate the ends of arms 61 and 62 is an arm 63 the end of which is of rounded or spherical form as indicated at 64, said end being adapted to cooperatively engage the upper closed and slightly depressed end 65 of a metallic cylinder or cup 66 which substantially encloses a spiral compression spring 67 which is interposed between the lever 57 and the contact carrier 68 of the switch.

Contact carrier 68, as best shown in Fig. 6 comprises a flat punched sheet metal member of substantially bail form, said carrier being adapted to embrace the base and the lower portions of the sides or arms of the switch frame. The adjacent inner edges of said carrier are provided with aligned projections 69 and 70 the lower edges 71 and 72 of which are adapted to bear upon the convergent walls of perforations 45 and 46 in the frame upon assembly of the parts.

To facilitate assembly of the carrier with respect to the frame and to provide for assembly of these parts by hand, the former is provided beneath the bearing edges 71, 72 thereof with outwardly stepped or cut away portions 73 and 74. It will be apparent that by this arrangement either of the projections 70 or 69 and the respective stepped portions therebeneath may be inserted bodily into one or the other of the openings 45, 46 in the frame, such insertion requiring a slight tilting of the carrier in its own plane, and the cut away portions 73, 74 being adapted to accommodate the portions 48 or 49 of the frame arms.

Thereupon the carrier may be tilted in the opposite direction in its own plane to bring the other projection 69 or 70 into alignment with the other perforation 46 or 45 in the frame arms. The carrier is then shifted axially to bring each of the lower edges 71 and 72 into cooperative engagement with the respective bearing openings. When assembling the parts in the manner just described it is preferable to engage the lower end of spring 67 with the abutment 75 provided on the carrier, the cylinder or cup 66 at the same time being held in an angular relation to pro-

vide for accommodation of the edge portions 76 of the carrier within the diametrically opposed slots or notches 77, 78 in the lower end of the cylinder as the spring is compressed by the assembling operation. Thus the carrier will be securely held in operative relation to the frame by a simple interlocking engagement of the parts.

As best shown in Fig. 6 the carrier 68 is provided with a pair of integral projections 79 and 80 the inner ends of which are provided with shoulders 81 and 82 which are adapted to interlock with the outwardly offset portions 83 and 84 of a substantially elliptical metal washer or plate 85. A duplicate but reversely arranged outer metal washer 86 is likewise provided, said washers having nested therebetween the relatively larger substantially rectangular insulating plates 87 and 88—the oppositely offset portions of said insulating plates being adapted to extend into correspondingly shaped openings in the resilient contact elements 89 and 90, which are of usual form. With the ends of projections 79 and 80 riveted over as shown in Fig. 6 the contacts are rigidly secured to the carrier but in properly insulated relation with respect thereto.

With the parts assembled upon the switch frame in the manner aforescribed the latter may be inserted into the recess in base 20 until it rests upon the soft rubber blocks 34 and 35, the projections 39 and 40 on the frame base being positioned between the opposed walls of end channels 28 and 29 as aforesated.

Located at one corner of the base 20 and upon the upper face 21 thereof is a terminal member 91, said member having a tapped opening 92 for cooperation with a screw 93 penetrating an opening 94 in the base whereby the former is rigidly secured to the latter. Member 91 is provided with the usual tapped opening 95 for cooperation with the shank of a binding screw 96,—base 20 being provided with a cavity to accommodate said binding screw.

Integral with member 91 and extending downwardly and then inwardly with respect thereto is a portion 97 (Fig. 12) which is shaped as indicated at 98 to form the lower stationary contact of the switch. The terminal member 99 at the other end of base 20 is secured to the latter in a similar manner,—said member having a slightly upwardly and then inwardly projecting integral portion 100 which is shaped as indicated at 101 to form the upper stationary contact of the switch.

As best shown in Fig. 3 the arm portions 43, 53 and 44, 54 of the switch frame extend a considerable distance above the base 20, and said portions are adapted to be cooperatively engaged by the walls of correspondingly shaped notches 102, 103 and 104, 105 on the

under face of an insulating cover member 106. Said cover member is provided with suitably formed cavities or recesses 107, 108 to accommodate the actuating lever and the movable contacts of the switch, and a notch or groove 109 is provided to accommodate the upwardly projecting portion 100 of stationary contact 101. Cover member 106 is likewise provided with an elongated rectangular opening 110 to permit oscillatory movement of the insulating handle portion 60 of the actuating lever while acting to prevent substantial lateral movement of the latter.

The ends of cover member 106 are formed as shown at 111 and 112 to expose the binding screws 96, whereby wiring of the switch is facilitated. Also as shown in Fig. 10 the cover member is provided with shoulders 113 and 114 adapted for cooperative engagement with the edges 115 and 116 of terminal members 91 and 99 whereby proper alinement of the stationary contacts is maintained.

The upper face of cover member 106 is provided at opposite ends thereof with suitable recesses 117 and 118 to receive the supporting lugs 119 and 120; common means such as screws 121 and 122 being employed to secure said insulating base and cover member to each other and to the supporting lugs. Said supporting lugs may be of usual form, but the same preferably comprise integral plaster engaging portions 123, 124, as shown in Figs. 2, 5 and 11.

As will be understood the arrangement is preferably such that upon complete assembly of the switch and casing parts the frame will be pressed to a certain degree into engagement with the rubber blocks, whereas the inherent resiliency of the latter provides a sort of floating support for the switch mechanism. By this means I provide for self-adjustment of the movable contacts with respect to the stationary contacts of the switch. Moreover, by arranging the parts in a manner to utilize the yielding faces of the rubber blocks as abutments for the contact carrier and actuating lever of the switch, I have provided a switch mechanism which is substantially noiseless in operation, and in which the life or durability of the cooperating switch parts is very greatly increased.

As best illustrated in Fig. 11 the insulating base and cover member may be shaped to give a pleasing appearance and the cover member may be further provided with suitable decorative paneling and stippling, as shown at 125.

The double pole switch illustrated in Figs. 4, 5 and 8 is in many respects substantially like that aforescribed. However, in this case the insulating base and cover members are somewhat widened and suitably recessed to accommodate a pair of movable contacts 89^a, 90^a at each side thereof, the carrier 68^a being provided with two pairs of projections

79^a, 80^a for support of said contacts. The metal frame employed is identical with that aforedescribed, and the switch parts may be assembled in the manner set forth above. The terminal members 91^a, 99^a and their associated stationary contacts 98^a, 101^a are identical with the stationary contacts of the single pole switch, whereas the similar but oppositely arranged terminal members 91^b, 99^b are respectively provided with lower and upper stationary contact portions 98^b, 101^b. The switch mechanism is assembled with respect to the insulating casing in the manner aforedescribed, and the insulating cover member may be suitably decorated as shown at 125^a.

What I claim as new and desire to secure by Letters Patent is:

1. In an electric snap switch, in combination, a cup-shaped insulating base having a recess therein, a soft rubber cushion resting upon the bottom wall of said recess, a substantially U-shaped metal frame having its flat bottom surface resting loosely upon said rubber cushion, and an insulating cover member for said base, said cover member having means engaging the arms of said U-shaped frame to assist in positioning the latter and to retain the same in assembled relation to said base.

2. In an electric snap switch, in combination, a cup-shaped insulating base having a recess therein, a soft rubber cushion resting upon the bottom wall of said recess, a substantially U-shaped metal frame having its flat bottom surface resting loosely upon said rubber cushion, an insulating cover member for said base, said cover member having means engaging the arms of said U-shaped frame to assist in positioning the latter and to retain the same in assembled relation to said base, supporting means for said base, and common means for securing said base and cover member to each other and to said supporting means.

3. In an electric snap switch, in combination, a cup-shaped insulating base having a recess therein, a pair of soft rubber blocks resting upon the bottom wall of said recess in spaced relation to each other, a substantially U-shaped metal frame the base portion of which is adapted to rest upon said rubber blocks and the arms of which extend upwardly beyond said insulating base, an insulating cover member for said base, said cover member having notches the walls of which engage the arms of said frame to hold the latter against substantial upward or horizontal movement relative to said insulating base, a contact carrier pivoted to said frame and oscillatable between the opposed faces of said rubber blocks, an operating lever pivoted to said frame and extending outwardly through said cover member, and a coiled compression spring interposed between said lever and said contact carrier.

4. In an electric snap switch, in combination, a cup-shaped insulating base having a recess therein, a pair of soft rubber blocks resting upon the bottom wall of said recess in spaced relation to each other, a substantially U-shaped metal frame the base portion of which is adapted to rest upon said rubber blocks and the arms of which extend upwardly beyond said insulating base, the opposed longitudinally spaced walls of said recess having aligned vertical channels and the base portion of said frame having projections to be positioned between the side walls of said channels, an insulating cover member for said base, said cover member having notches the walls of which engage the arms of said frame to hold the latter against substantial upward or horizontal movement relative to said insulating base, a contact carrier pivoted to said frame and oscillatable between the opposed faces of said rubber blocks, an operating lever pivoted to said frame and extending outwardly through said cover member, and a coiled compression spring interposed between said lever and said contact carrier.

5. A substantially noiseless snap switch of the flush type comprising a two-part enclosing casing of molded insulating material, a cavity within said casing, a plurality of soft rubber cushions located in spaced relation to each other upon one wall of said cavity, a substantially U-shaped sheet metal frame engaged by another wall of said cavity and held in pressing engagement with said rubber cushions, a flat stamped sheet metal contact carrier pivotally supported by said frame and oscillatable from one extreme position to the other into alternate engagement with the opposed faces of said rubber cushions, an actuating lever pivotally supported by the arms of said frame, said lever having elongated projections upon opposite sides of the pivot point thereof, the base portion of said frame having perforations to permit passage of said projections therethrough into engagement with said rubber cushions to thereby yieldably limit oscillatory movement of said lever, and a coiled compression spring interposed between said lever and said contact carrier to effect snap movements of the latter upon predetermined movements of the former.

6. In an electric snap switch, in combination, a stamped sheet metal frame of substantially U-shape in cross section, the upwardly extending arms of said frame each having a relatively large perforation forming a closed bearing, the material of said frame being cut away beneath each perforation in conformity with the latter and across the base of the frame, a flat stamped sheet metal contact carrier of substantially U-shape

- adapted to embrace said frame, the adjacent inner edges of said carrier having alined projections adapted for cooperation with the bearings in said frame, the material of said carrier being cut away beneath said projections in outwardly stepped relation to provide portions which are readily insertable individually within either of said bearing openings upon tilting of said carrier, whereupon 5 said carrier may be swung in its own plane to provide for alinement of the opposite projection and its cooperating bearing, said carrier being shiftable axially with respect to the frame to bring the parts into assembled relation, a rock lever pivoted to the frame above the carrier, and a coiled compression spring interposed between one end of said lever and said carrier to retain the latter in assembled relation to the frame.
- 10 7. In an electric snap switch, in combination, a stamped sheet metal frame of substantially U-shape in cross section, the upwardly extending arms of said frame each having a relatively large perforation of substantially inverted triangle shape forming a closed bearing adjacent to the lower end thereof, the material of said frame being cut away beneath each perforation in conformity with the latter and across the base of the frame, 15 a flat stamped sheet metal contact carrier of substantially U-shape adapted to embrace said frame, the adjacent inner edges of said carrier having alined projections adapted for cooperation with the bearings in said frame, the material of said carrier being cut away beneath said projections in outwardly stepped relation to provide portions which are readily insertable bodily within either of said bearing openings upon tilting of said carrier, 20 whereupon said carrier may be swung in its own plane to provide for alinement of the opposite projection and its cooperating bearing, said carrier being shiftable endwise with respect to the frame to effect engagement of both 25 projections with their respective bearings, the vertical edges of said stepped portions being adapted to engage the outer surfaces of the frame arms to restrain said carrier against further axial movement, a toggle lever pivotally supported between the arms of the frame above said carrier, and a coiled compression spring interposed between the lower end of said lever and said carrier to retain the latter in assembled relation to the frame 30 and to effect snap movements of said carrier from one extreme position to the other upon predetermined movements of said lever.
- 35 8. In an electric snap switch, the combination with a sheet metal frame of substantially U-shape in cross section, the upwardly extending sides of said frame having relatively large alined perforations forming closed bearings, of a flat stamped sheet metal contact carrier of substantially bail form adapted to embrace the bottom and sides of said frame, said carrier having alined inward projections the lower edges of which are arranged in outwardly stepped relation where- 40 45 50 55 60 65 70 75 80 85 90 95 100 105 110 115 120
- said frame, said carrier having alined inward projections the lower edges of which are arranged in outwardly stepped relation whereby either of said projections may be fully inserted into one of said bearing openings, said carrier being thereupon tiltable in its own plane to bring the other projection into alinement with its cooperating bearing opening and said carrier being shiftable axially with respect to the frame to bring each of the upper stepped edges of said projections into pivotal engagement with said bearing openings, the vertical portions of said stepped edges cooperating with the frame sides to restrain said carrier against further axial movement in either direction, a toggle lever pivotally supported above said carrier, and a spiral compression spring interposed between one end of said lever and said carrier.
9. In an electric snap switch, the combination with a sheet metal frame of substantially U-shape in cross section, the upwardly extending sides of said frame having relatively large alined perforations forming closed bearings, of a flat stamped sheet metal contact carrier of substantially bail form adapted to embrace the bottom and sides of said frame, said carrier having alined inward projections the lower edges of which are arranged in outwardly stepped relation whereby either of said projections may be fully inserted into one of said bearing openings, said carrier being thereupon tiltable in its own plane to bring the other projection into alinement with its cooperating bearing opening and said carrier being shiftable axially with respect to the frame to bring each of the upper stepped edges of said projections into pivotal engagement with said bearing openings, the vertical portions of said stepped edges cooperating with the frame sides to restrain said carrier against further axial movement in either direction, a toggle lever pivotally supported above said carrier, and a spiral compression spring interposed between one end of said lever and said carrier.
10. In an electric snap switch, the combination with a sheet metal frame of substantially U-shape in cross section, the upwardly extending sides of said frame having relatively large alined perforations forming closed bearings, of a flat stamped sheet metal contact carrier of substantially bail form adapted to embrace the bottom and sides of said frame, said carrier having alined inward projections the lower edges of which are arranged in outwardly stepped relation where-

by either of said projections may be fully inserted into one of said bearing openings, said carrier being thereupon tiltable in its own plane to bring the other projection into alignment with its cooperating bearing opening and said carrier being shiftable axially with respect to the frame to bring each of the upper stepped edges of said projections into pivotal engagement with said bearing openings, the vertical portions of said stepped edges cooperating with the frame sides to restrain said carrier against further axial movement in either direction, a toggle lever pivotally supported above said carrier, a spiral compression spring interposed between one end of said lever and said carrier, the base of said frame being cut away to accommodate said spring and the bottom portion of said carrier, and a cylindrical metal member substantially enclosing said spring, said member having a closed and indented end engaged by said lever, the other end of said member having aligned notches for sliding engagement with said carrier, said member cooperating with said frame to positively initiate movement of said carrier from each extreme position to the other.

11. In an electric snap switch, the combination with a molded insulating base having a main recess, the bottom wall of said recess having vertical shoulders or abutments forming relatively shallow dove-tail recesses at opposite ends of said base, a pair of soft rubber blocks snugly fitting within said last mentioned recesses and held against movement in a given plane by the angular walls of the latter, said blocks extending a substantial distance above the shoulders which form said recesses, a sheet metal frame the base of which is adapted to rest upon said blocks, a flat stamped sheet metal contact carrier depending from said frame and oscillatable from one extreme position to the other into engagement with the respective rubber blocks, a molded insulating cover member for said base, and means on said cover member adapted for interlocking engagement with said frame to retain the latter in assembled relation to said base.

12. In an electric snap switch, in combination, a stamped sheet metal frame of substantially U-shape in cross section, the upwardly extending arms of said frame each having a relatively large perforation forming a closed bearing, the material of said frame being cut away beneath each perforation in conformity with the latter and across the base of the frame, a flat stamped sheet metal contact carrier of substantially U-shape adapted to embrace said frame, the adjacent inner edges of said carrier having aligned projections adapted for cooperation with the bearings in said frame, the material of said carrier being cut away beneath said projections in outwardly stepped relation to provide

portions which are readily insertable individually within either of said bearing openings upon tilting of said carrier, whereupon said carrier may be swung in its own plane to provide for alignment of the opposite projection and its cooperating bearing, said carrier being shiftable axially with respect to the frame to bring the parts into assembled relation, a rock lever pivoted to the frame above the carrier, a coiled compression spring interposed between one end of said lever and said carrier to retain the latter in assembled relation to the frame, an insulating base having a recess, a pair of soft rubber blocks located in spaced relation to each other upon the bottom wall of said recess, said metal frame resting upon said blocks and the arms of the former projecting upwardly beyond said insulating base, an insulating cover member having notches the walls of which engage the arms of said frame to retain the latter in assembled relation to said base, a pair of supporting lugs for said base, and common means for securing said base and cover member to each other and to said supporting lugs.

13. In an electric snap switch, the combination with a sheet metal frame of substantially U-shape in cross section, the upwardly extending sides of said frame having relatively large aligned perforations forming closed bearings, of a flat stamped sheet metal contact carrier of substantially bail form adapted to embrace the bottom and sides of said frame, said carrier having aligned inward projections the lower edges of which are arranged in outwardly stepped relation whereby either of said projections may be fully inserted into one of said bearing openings, said carrier being thereupon tiltable in its own plane to bring the other projection into alignment with its cooperating bearing opening and said carrier being shiftable axially with respect to the frame to bring each of the upper stepped edges of said projections into pivotal engagement with said bearing openings, the vertical portions of said stepped edges cooperating with the frame sides to restrain said carrier against further axial movement in either direction, a toggle lever pivotally supported above said carrier, a spiral compression spring interposed between one end of said lever and said carrier, the base of said frame being cut away to accommodate said spring and the bottom portion of said carrier, a cylindrical metal member substantially enclosing said spring, said member having a closed and indented end engaged by said lever, the other end of said member having aligned notches for sliding engagement with said carrier, and a longitudinally divided two-part insulating casing having a pair of spaced soft rubber blocks upon which said switch frame is adapted to seat, said blocks

each having angularly arranged faces with which said toggle lever and said carrier are respectively adapted to engage to thereby yieldably limit the oscillatory movements of said parts.

5 14. A flush snap switch comprising a horizontally divided two-part insulating casing providing a cavity, a switch mechanism located within said cavity and clamped in position by said casing parts, soft rubber cushioning means interposed between one of said casing parts and said switch mechanism to provide a floating support for the latter, switch operating means projecting through 10 the other of said casing parts, and wiring terminal means readily accessible from the exterior of said casing.

15. A snap switch of the toggle type adapted for flush mounting, comprising a recessed molded insulating base, stationary contact and terminal members secured to said base at the corners thereof, soft rubber cushioning means seated upon the bottom wall of said recess, a switch mechanism comprising a metal frame seated upon said cushioning means, said frame having parts projecting above said base, a molded insulating cover member for said base, said cover member having interlocking engagement with the 20 projecting parts of said frame, a toggle actuating lever projecting through said cover member, and means for rigidly securing said base and cover members to each other whereby said frame is held in proper position, the 25 corners of said cover member being cut away to expose the terminal members on said base.

16. In an electric snap switch, in combination, a cup-shaped insulating base having a recess therein, a pair of spaced soft rubber blocks resting upon the bottom wall of said 30 recess and restrained against horizontal movement by shoulders formed on the latter, a substantially U-shaped metal frame the flat base portion of which is adapted to rest 35 loosely upon said rubber blocks and the arms of which extend upwardly beyond said insulating base, a member extending across the upper face of said insulating base, said member having notches the walls of which engage 40 the projecting arms of said frame to hold the latter against substantial upward or horizontal movement relative to said insulating base, a flat punched sheet metal contact carrier pivotally supported directly by said 45 frame and oscillatable between the opposed faces of said rubber blocks, an operating lever pivoted to said frame and extending outwardly through an opening in the member aforementioned, and a coiled compression 50 spring interposed between said lever and said contact carrier.

In witness whereof, I have hereunto subscribed my name.

RALPH A. MILLERMASTER.
